[57] CLAIM

The ornamental design for a protector housing for telecommunications equipment, as shown and described.

DESCRIPTION

FIG. 1 is a front elevational view of a protector housing for telecommunication equipment showing our new design;

FIGS. 2 and 3 are respectively top and bottom plan views thereof;

FIGS. 4 and 5 are respectively left and right side elevational views thereof;

FIG. 6 is a rear elevational view thereof;

FIG. 7 is a front elevation view thereof with the cover in an opened position;

FIG. 8 is a front elevation view thereof with the cover in an opened position, and the compartment door thereto also open and nested within the cover;

FIG. 9 is a bracket associated, exploded bottom plan view of the housing components in separated, unhinged, tandem relationship.

FIG. 1

FIG. 2

FIG. 3

FIG. 4

FIG. 5

FIG. 6

FIG. 7

FIG. 8

FIG. 9
